PERMANENTLY LUBRICATED SPRING CABINET TRAY ELEVATOR

Robert J. Shelley, Miami, Fla.

Application December 23, 1952, Serial No. 327,541

2 Claims. (Cl. 248—204)

This invention relates to improved bottle elevating devices in cooling cabinets such as cabinets used for beer, milk, soft drinks and the like and wherein the products are temporarily stored for cooling, and in particular a substantially sealed telescoping spring housing adapted to be positioned with units in opposite sides of a cabinet and with the ends secured to the cabinet, and wherein a tray carrying foot or shelf extends from the lower part of an outer telescoping tubular casing of each unit, and a permanent lubricator in which the spring is encased remains on the spring indefinitely.

The purpose of this invention is to provide a telescoping support for elevating trays in a cooling cabinet in which one of the telescoping members provides a guide for retaining tray carrying feet or shelves on the lower ends thereof in alignment.

This invention is an improvement over the tray mounting of my prior Patent No. 2,525,243 dated October 10, 1950, in that the telescoping elements are substantially sealed whereby a permanent lubricator may be retained on the spring and wherein the tray carrying foot forms an integral part of one of the telescoping tubes with the tube providing a guide therefor.

In a cooler for liquids, particularly in bottles and the like where bottle supporting trays are carried on springs on vertically positioned posts, the atmosphere is damp and the springs and mounting elements therefor corrode and rust rapidly. With this thought in mind this invention contemplates a telescoping tubular casing or housing positioned around the springs with the upper and lower ends substantially sealed and with an inner tube extended through the spring and housing whereby the springs may be covered with a lubricant and the lubricant protected, and wherein tray carrying elements may be positioned directly on the telescoping tubes with the tubes providing guides therefor.

The object of this invention is, therefore, to provide means for constructing a telescoping tubular housing for enclosing tray supporting springs whereby the complete spring is permanently lubricated and protected from rust, corrosion, or deterioration and wherein the housing provides a guide for retaining tray carrying elements in alignment.

Another object of the invention is to provide a substantially sealed telescoping tray supporting and elevating unit that is adapted to be installed in cabinets now in use.

A further object of the invention is to provide an improved spring actuated telescoping tray supporting unit in which lubricant may remain permanently on a spring therein and in which the unit provides a guide for retaining tray supporting elements in alignment, in which the device is of a simple and economical construction.

With these and other objects and advantages in view the invention embodies an elongated tubular post or core, a lower tubular casing positioned around the core and spaced therefrom, an upper telescoping tubular casing also positioned around the core, slidably mounted over the lower casing and having a tray supporting foot on

the lower end, and a spring extended around the core, positioned in the tubular casing and adapted to urge the upper tubular casing upwardly.

Other features and advantages of the invention will appear from the following description taken in connection with the drawing, wherein:

Figure 1 is a vertical section through the improved telescoping tray supporting unit showing a spring in the unit extended and showing the unit mounted on the inner surface of the wall of a cabinet with parts of the cabinet broken away.

Figure 2 is a view similar to that shown in Fig. 1 showing the spring partly contracted and with the upper tubular casing held with a pin extended through the tubular core whereby the device is adapted to be positioned in and removed from supporting elements in a cabinet.

Figure 3 is a side elevational view of the telescoping unit with the parts as shown in Fig. 2 and with the supporting elements omitted.

Figure 4 is a sectional plan through the unit taken on line 4—4 of Fig. 2 illustrating a portion of a tray positioned on a foot of the upper telescoping tube showing a locating notch in the end of the tray, the tray being shown in broken lines.

Referring now to the drawing wherein like reference characters denote corresponding parts the improved spring actuated tray elevating unit of this invention includes a continuous rod or tubular core 10, a lower tube 11, an upper telescoping tube 12, a shelf or foot 13 carried by the lower end of the tube 12 and a continuous spring 14.

The lower end of the tube 11 is provided with a filler 15 whereby the lower end of the tube 11 is sealed around the core 10 and the lower end of the core is provided with a plug 16 whereby the lower end of the core is sealed.

The upper end of the core 10 may be provided with a threaded plug 17, although it will be understood that the upper end of the core may remain open or may be closed by suitable means.

This unit including the telescoping tubes 11 and 12 mounted on the core 10 and urged toward extended positions with the spring 14 is mounted in cooling cabinets with the units aligned whereby trays may extend from one unit to another.

Trays, as indicated by the dotted lines 18, are provided with notches 19 whereby the trays are located and retained in positions on the feet 13 being freely positioned on the feet or shelves, and the trays may be removed and replaced with the tubes in extended or contracted positions, as may be desired.

In the design illustrated in Figs. 1 and 2 the units are mounted on a side wall of a cabinet with the lower end of the core of each unit inserted in an opening 20 in a bracket or clip angle 21 and the upper end of the core 10 is held in an opening 22 of a similar clip angle 23. In the design shown the supporting clip angles are secured to a side wall 24 of a cabinet with screws 25, however, it will be understood that the mounting elements 60 may be secured to the wall of the cabinet by welding, soldering, braising, or other suitable means; or the lower ends of the cores may be inserted in openings in the floor or base of the cabinet and the upper end secured in clip angles, rails, or other parts of the cabinets.

The upper end of the upper tube 12 is closed with a washer 26 that may be braised or welded in the end of the tube and the core or tube 10 is provided with an opening 27 through which a pin 28 may be temporarily placed to retain the upper tube in the position shown in Figs. 2 and 3 to facilitate inserting the unit in a cabinet or the like.

As the ends of the rods or cores 10 are secured in openings in the cabinet or in brackets positioned therein the pin 28 is withdrawn and the spring 14 urges the upper tube upwardly to the position shown in Fig. 1.

With the parts formed in this manner the springs are completely enclosed so that they may be coated with a permanent lubricating grease and with the spring encased in grease continuously substantially all noise is eliminated and the unit operates quietly and continuously. Furthermore, with the springs and inner surfaces of the tubes coated with grease the upper telescoping tube travels smoothly and silently on the lower tube.

This improved structure makes it possible to hold the foot or supporting element of the tray in alignment without braces or other attaching means and with the units accurately mounted in vertical positions the trays travel downwardly when bottles are positioned thereon and are elevated as the bottles are removed.

It will be understood that modifications, within the scope of the appended claims, may be made in the design and arrangement of the parts without departing from the spirit of the invention.

What is claimed is:

1. In a resilient tray supporting unit, the combination which comprises a tubular core having closures in the ends thereof, a lower tube positioned around said core, sealing means connecting the lower end of said lower tube to the core at a point spaced from the lower end of the core, an upper telescoping tube also positioned around said core and slidably mounted on said lower tube, the upper end of said upper tube having a closure therein and said core extended through said closure, a tray carrying foot integral with and extended from the lower end of the upper tube, and a spring around said core and positioned with the ends in engagement with

the sealing and closure means of the lower and upper tubes, respectively, and lubricating means within said tubes about said spring.

2. In a resilient tray supporting unit, the combination which comprises a tubular core having closures in the ends thereof, a lower tube positioned around said core, sealing means connecting the lower end of said lower tube to the core at a point spaced from the lower end of the core, an upper telescoping tube also positioned around said core and slidably mounted on said lower tube, the upper end of said upper tube having a closure therein and said core extended through said closure, a tray carrying foot integral with and extended from the lower end of the upper tube, a spring around said core and positioned with the ends in engagement with the sealing and closure means of the lower end upper tubes, respectively, grease positioned in the area between the tubular core and upper and lower tubes and said spring being substantially embedded in said grease and means engaging the ends of said core for mounting said unit in a cabinet, or the like.
